COMBINED MUFFLER AND HEATER

Original Filed May 24, 1924 2 Sheets-Sheet 2

UNITED STATES PATENT OFFICE.

WALTER A. KYSOR, OF ALLEGAN, MICHIGAN.

COMBINED MUFFLER AND HEATER.

Original application filed May 24, 1924, Serial No. 715,307. Divided and this application filed January 24, 1925. Serial No. 4,543.

This invention relates to a combined muffler and heater for use on motor driven vehicles, in which the impulses of the exhaust gas are silenced, and the heat of this gas is utilized for heating a current of air, which may be caused to circulate through the tonneau.

The general object of the invention is to provide a device of this character which is comparatively simple and inexpensive in its construction, practical and efficient in its operation, and which, in its preferred form, may be built as a single unit to be installed in place of the ordinary muffler now used.

The invention herein claimed includes certain features which have been divided from my co-pending application, Serial No. 715,307, filed May 23, 1924, and also embodies certain improvements over the construction disclosed in said application. The structure of the invention and the cooperative relation between the passageway for the exhaust gases and the passageway for the current of air to be heated is such that not only is the muffling action improved, but the heating of the air current and its circulation through the tonneau is promoted.

The specific construction of the invention, as well as its objects and advantages, will be more fully explained in connection with the accompanying drawings, which illustrate the same in its preferred form.

In the drawings:

Figure 1 is a side elevation of the invention, illustrating the same in connection with a portion of an automobile chassis.

Figure 2 is a vertical longitudinal section through the muffling and heating chambers.

Figure 3 is an enlarged cross section taken on the line 3-3 of Figure 2.

Figure 4 is an enlarged cross section taken on the line 4-4 of Figure 2.

Figure 5 is an enlarged cross section taken on the line 5-5 of Figure 2.

Figure 6 is an enlarged cross section taken on the line 6-6 of Figure 2.

Figure 7 is an enlarged detail sectional view of the rear portion of the invention.

Figure 8 is a similar detail view of the front portion of the invention.

The invention, as herein disclosed, includes an inner rearwardly tapered steel pipe 10

of comparatively heavy gage, and having an enlarged front end formed by a tapered thimble 11, secured thereto in any suitable manner.

Surrounding the tapered pipe 10 and spaced therefrom is a heating chamber 12, formed by inner and outer concentric cylindrical walls 13 and 14, which are maintained in their relative positions by annular flanges 15 and 16 interposed between their respective ends. One of these flanges, as 15, is welded or otherwise secured to both of the walls 13 and 14, while the other flange 16 is welded to the outer wall 14, and has a close, sliding, substantially air-tight fit on the inner wall 13, which projects some distance beyond the end of the outer wall. This allows for the unequal longitudinal expansion of the two walls, resulting from differences in temperature, and without unduly straining the connections, or causing one of the walls to buckle.

The forwardly projecting end of the wall 13 is secured to the enlarged outer portion of the thimble 11 by suitable screws 17 or the like, which also serve to secure a reducer coupling member 18, adapted to receive the rear end of the exhaust pipe 19. It is, of course, obvious that couplings of different sizes may be manufactured to fit the various sizes of exhaust pipes used on different motor vehicles.

The rearwardly tapered pipe 10 is provided with numerous holes 20, through which the exhaust gases may pass into contact with the inner wall 13 of the heating chamber, the holes in the front portion of the pipe being more numerous than those in the rear portion thereof. The rear end of the pipe 10 has a plug 21 secured therein, which has only a restricted opening 22 therethrough, so that the greater portion of the exhaust gases will be forced outwardly through the holes 20 and come in contact with the wall 13. A number of annular baffle plates 23 are secured around the rear portion of the pipe 10, and extend nearly to the wall 13. These baffle plates tend not only to further silence the motor impulses, but also to retard the backward flow of the exhaust gas, and promote its heating action upon the wall 13 of the heating chamber.

The rearmost baffle plate 23 is attached to the wall 13 by one or more steel cleats 24 which are welded thereto, and serve to support the rear end of the tapered pipe 10, and 5 eliminate vibration of the same.

The inner wall 13 is extended at its rear end beyond the end of the outer wall 14, and is provided internally with a reinforcing ring 25, which forms a backing plate for 10 screws 26 used for attaching a secondary muffling chamber 27. This chamber is substantially cylindrical, and within it are secured a plurality of baffle plates 28, each having a central orifice 29, alternating with 15 smaller circular baffle plates 30, which are supported with their edges spaced from the wall of the chamber, so that the gases entering the front end of the chamber pass alternately around the peripheries of the plates 20 30, and through the central openings 29 in the plates 28. The rear end of the chamber 27 is provided with an outlet nipple 31 to which may be attached a tail pipe 32 of the usual construction for carrying the 25 exhaust gases to the extreme rear of the car.

The walls of the air chamber 12 are imperforate, except for an inlet nipple 33 opening tangentially into the bottom of the outer wall 14 near its forward end, and an outlet 30 nipple 34 opening tangentially from the upper portion of the wall 14 near its rear end. A flexible metal conduit, or a tubular conduit of ordinary pipe, may be clamped to the nipple 34 and arranged to conduct a 35 current of air from the chamber 12 into the tonneau. The other nipple 33 may be connected by a similar conduit to a funnel-shaped intake placed directly back of the motor fan, so as to establish a continuous 40 forced circulation of air through the heating chamber 12 and into the tonneau.

In the preferred installation, as indicated in Figure 1, the combined muffler and heater is hung in the frame 35 of the chassis, in the 45 usual position of the conventional muffler. The air for heating the tonneau is conducted through a flexible conduit 36 which is located at one side of the motor, and terminates at its forward end in a funnel-shaped 50 mouth 37 located in rear of the fan 38. The rear end of the conduit 36 is connected by an elbow to the inlet nipple 33. By this construction, a forced draft is obtained through the heating chamber 12, which is 55 also the cleanest air obtainable, since it comes from in front of the car, and it is also somewhat warmed by its flow through the radiator of the car. The tangential disposition of the nipple 33 causes the current of air to 60 travel spirally between the walls 13 and 14, and to become thoroughly heated. A conduit 39 is connected to the outlet nipple 34, and leads to the interior of the tonneau. This conduit is preferably provided with a valve housing 40, containing a three-way

valve 41, this valve being provided with a crank arm 42, having a connection 43 extending to a point within convenient reach of the driver, so that the valve may be actuated to discharge the heated air into the 70 tonneau, or laterally through an opening 44 into the atmosphere.

It will be noted that the inner wall of the air drum or conduit lies in close proximity to the perforated discharge pipe for the 75 heated gases. In certain of the commercial structures embodying the features of the invention the distance between the larger end of the pipe and the inner wall of the drum is approximately three-quarters of an inch 80 while at the rear end the distance is approximately an inch and a half, the inner wall being of a diameter of four and three-fourths inches and the outer wall six and one-half inches, the length being thirty-two 85 and one-half inches. This is the dimension of the commercial structure as I have built the same for passenger cars.

With the parts thus arranged the heated gases or products of combustion are discharged through the perforations in the discharge pipe in jets impinging directly against the inner wall of the air conduit so that a very large percentage of the heat may be absorbed or taken up by the air passing 90 through the conduit, the air drum providing a gas chamber through which the products of combustion are discharged to the auxiliary muffler device described. The discharge from this chamber is restricted by the baffle 95 plates 23.

The restricted discharge opening 22 in the plug 21 at the rear end of the discharge pipe is of advantage in that carbon and other solids are effectively discharged through this 100 opening, thereby preventing their accumulation within the discharge pipe. I preferably provide lateral perforations close to this plug which further facilitates the discharge of solids, at the same time compelling 105 the bulk of the heater gases to be discharged through the side orifices in impinging relation, as stated, to the inner wall of the air conduit.

As a very substantial percentage of the 110 heat is taken up by the air, the pressure of the heated gases is very substantially reduced, thus adding to the muffling effect and reducing back pressure on the motor.

The device is very efficient both from the 115 standpoint of its heating capacity and its muffling capacity without serious back pressure. There is, in fact, much less back pressure than is present in the type of mufflers commonly used.

While I have shown and described specifically the various features of the invention in what is at present their preferred form, it is to be understood that these are subject to modification, as long as such modi- 120 125 130

fication does not include any material departure from the principles upon which the operation of the invention is based. It is, therefore, my intention to include all such 5 modifications within the scope of the appended claims.

What is claimed is:

1. In a device of the class described, the combination of concentrically disposed inner 10 and outer tubular walls providing a central elongated gas chamber and a surrounding air chamber, said air chamber having air inlet and discharge openings at the ends thereof, said gas chamber having an annular gas 15 discharge opening at its rear end, and a rearwardly tapered discharge pipe for heated gases disposed centrally within said gas chamber and extending approximately from end to end thereof, the diameter of said pipe 20 at its larger end being such that it lies close to the said inner wall, said pipe having a plurality of side discharge orifices disposed around it so that the heated gases are discharged therefrom in laterally directed jets 25 and thence flow longitudinally through said

gas chamber around said pipe to said gas discharge opening at the rear end thereof.

2. In a device of the class described, the combination of inner and outer tubular walls providing a central elongated gas 30 chamber and a surrounding air chamber, said air chamber having air inlet and discharge openings at the ends thereof, said gas chamber having a gas discharge opening at its rear end, and a discharge pipe 35 for heated gases disposed longitudinally within said gas chamber, the diameter of said pipe being such that it lies relatively close to the said inner wall, said pipe having a plurality of side discharge orifices disposed around it so that the heated gases are discharged therefrom in laterally directed jets against the said inner wall and thence flow rearwardly in said gas chamber around 40 said pipe to said gas discharge opening at 45 the rear end thereof.

In testimony, that I claim the foregoing as my own, I have hereto affixed my signature.

WALTER A. KYSOR.
